HAIRPIN

Howard Weston Hawkinson, Rochester, N. Y.

Application October 2, 1934, Serial No. 746,602

3 Claims. (Cl. 132—50)

This invention relates to hairpins, and its general object is to provide a hairpin in the form of a clasp that is capable of clamping the strands of hair of the user against displacement in all directions as the hair is held thereby both crosswise and lengthwise and casual removal of the clasp is practically impossible.

A further object of the invention is to provide a hair clasp that can be easily and expeditiously associated with and removed from the hair, will lay flat to the head, is simple in construction, inexpensive to manufacture, and extremely efficient in use and service.

This invention also consists in certain other features of construction and in the combination and arrangement of the several parts, to be hereinafter fully described, illustrated in the accompanying drawing, and specifically pointed out in the appended claims.

In describing my invention in detail, reference will be had to the accompanying drawing wherein like characters denote like or corresponding parts throughout the several views, and in which:

Figure 1 is a side elevation of the clasp which forms the subject matter of the present invention.

Figure 2 is a top plan view thereof.

Figure 3 is a sectional view taken approximately on line 3—3 of Figure 1.

Referring to the drawing in detail, the clasp which forms the subject matter of the present invention is formed from resilient material such as spring steel and includes a relatively narrow elongated body in the form of a frame that is provided with slightly spaced parallel members 1 that merge into rounded ends 2.

Formed on one of the ends to extend at right angles with respect thereto is a coil in the form of an eye 3, and this eye has formed thereon one end of an arm 4 which is waved in serpentine formation as best shown in Figure 1. The arm 4 may be formed from flat material as shown and extends between the parallel members 1 in a manner whereby the successive substantially semi-circular portions of the waves thereof are disposed above and below the plane of the parallel members 1 as clearly shown in Figure 1. The arm 4 is of a width whereby the side edges thereof are disposed in close proximity to the parallel members 1, and the free end of the arm 4 terminates in a tongue 5 that cooperates with the opposite end of the body to set up a clamping action which is brought about by the resiliency of the eye 3.

From the above description and disclosure of

the drawing, it will be obvious that I have provided a hairpin in the form of a clasp that can be easily and expeditiously applied to the hair of the user, due to the fact that the arm 4 has one of its ends free and can be readily separated from its body against the action of the eye or coil 3, to receive a relatively great number of strands of hair. When the arm is released, the coil or eye 3 causes the arm to fall within the space between the parallel members 1, with the result the hair will be positively clamped against displacement in all directions, and casual removal of the clasp is practically impossible, therefore the clasp not only holds the hair as desired by the user, but loss of the clasp is reduced to a minimum, in that it cannot be lost when in use.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A hairpin in the form of a clasp comprising an elongated body including spaced parallel members, a relatively wide arm having one end readily secured to one end of the body and disposed between the parallel members thereof, said arm being waved in serpentine formation and a tongue formed with the free end of the arm for cooperation with the opposite end of the body.

2. A hairpin in the form of a clasp made from resilient material and comprising an elongated body including spaced parallel members, rounded ends for the body and having the spaced parallel members merging therein, an arm waved in serpentine formation, resilient means securing one end of the arm to one end of the body and being in the form of a coil, said arm being arranged between the spaced parallel members with its side edges disposed in close proximity thereto, and so that the successive waves are disposed above and below the parallel members, a tongue formed on the free end of the arm for association with the body.

3. A hairpin in the form of a clasp comprising an elongated body including spaced parallel members, a waved member, and curved resilient means connecting the waved member to one end of the body for disposing the waved member between the parallel members in spaced relation thereto for cooperation therewith.

HOWARD WESTON HAWKINSON. 55
